DISPLAY RACK

Carl T. Lundstrom and Edward A. McLaughlin,
Terre Haute, Ind.

Application May 22, 1937, Serial No. 144,259

1 Claim. (Cl. 211—149)

The present application relates to a display rack. The primary object of the invention is to provide a rack of improved appearance and mechanical construction which shall provide a maximum of shelf space for display purposes; and yet which shall be so constructed that it may be folded into a compact, flat package, for transportation. A further object of the invention is to provide a device of the character described which, when assembled for use, shall be extremely rigid, in spite of its folding characteristics. Further objects of the invention will appear as the description proceeds.

To the accomplishment of the above and related objects, our invention may be embodied in the form illustrated in the accompanying drawing, attention being called to the fact, however, that the drawing is illustrative only, and that change may be made in the specific construction illustrated and described, so long as the scope of the appended claim is not violated.

Fig. 1 is a front elevation of a rack constructed in accordance with the present invention;

Fig. 2 is a side elevation thereof;

Fig. 3 is a fragmental vertical section taken substantially in the plane of line 3—3 of Fig. 1 and looking in the direction of the arrows;

Fig. 4 is a fragmental horizontal section taken substantially in the plane of line 4—4 of Fig. 2 and looking in the direction of the arrows;

Fig. 5 is a fragmental horizontal section taken substantially in the plane of line 5—5 of Fig. 2 and looking in the direction of the arrows; and

Fig. 6 is a fragmental section taken substantially in the plane of line 6—6 of Fig. 2 and looking in the direction of the arrows.

Referring more particularly to the drawing, it will be seen that I have illustrated a rack comprising a substantially rectangular back frame 10, said frame being preferably formed of tubing bent to provide lateral uprights 11, a top piece 12, and a bottom piece 13. Preferably, feet 14 are suitably secured to the bottom piece 13 of the back frame 10. If desired, the back may be suitably braced by cross rods 15 secured in aligned apertures in the lateral uprights 11 thereof.

A side wing frame 16 is likewise preferably formed from tubing bent into a substantially rectangular shape to provide lateral uprights 17 and 18, a top piece 19 and a bottom piece 20, feet 21 being preferably secured to the bottom piece 20. Preferably, the frame 16 is suitably braced by crossbars 22 secured at their opposite ends in aligned apertures in the lateral uprights 17 and

18. A second substantially allochiral side wing frame 16' is provided.

The reference numerals 23, 24, and 25 indicate generally shelves or trays, each of which comprises a substantially rectangular frame preferably formed of strip metal bent to form front and rear edges 26 and 27 and joining end pieces 28 and 29; each of said frames carrying a sheet 30 of expanded metal or other preferably foraminous material. As will be readily seen from 10 a consideration of Figs. 3 and 4, each shelf frame actually comprises two pieces of strip metal, the portions 26', 27', and 28' thereof being specifically shown. Said two pieces of strip metal are clamped together to secure therebetween the 15 downturned edges 31 of sheet 30.

The side wing frames 16 and 16' are suitably hinged to the lateral uprights 11 of the back frame 10. Preferably, said side wing frames are hinged through the medium of straps 32, one of 20 which is illustrated in detail in Fig. 5. Each of the straps 32 comprises a semi-cylindrical end portion 33 embracing an upright 11, a semi-cylindrical portion 34 embracing an upright 17 or 17', and side portions 35 and 36 joining the 25 end portions 33 and 34. Preferably, the major dimension of each strap 32 exceeds the sum of the diameters of the uprights 11 and 17 or 17', whereby each side wing frame may be folded 30 into a plane parallel with the plane of the back frame 10, to lie flat against said back frame 10.

In Fig. 5 is illustrated a preferred means for joining the ends of the tubing from which the frames are formed. A tube 37 having an external diameter substantially equal to the internal diameter of the tube the ends of which are to be joined, is inserted into the two adjacent ends thereof, and is secured in place by screws 38, one or more of which preferably penetrates 35 each of the tubing ends to be joined.

The shelves 23, 24, and 25 are pivotally suspended from the lateral uprights 11 of the back frame 10 through the medium of pins 39 projecting laterally from each end of each shelf adjacent the rear edge thereof. If desired, said pins 45 39 may be extensions of the screws whereby the strips 28' and 29' are clamped to the strips 28 and 29. Each of said pins 39 projects into a suitably formed aperture in an upright 11 of the back frame 10; and it will be understood that 50 oppositely projecting pins 39 carried by each shelf will be received in aligned apertures in the two respective uprights 11 of the back frame 10.

The lateral uprights 18 and 18' of the respective side wing frames 16 and 16' carry respec- 55

- tively a plurality of brackets 40 or 40', the number of brackets being equal to the number of shelves or trays in the organization. Each bracket 40 or 40' is secured in place by a screw 41 or 41' projecting into a suitably formed threaded aperture in the upright 18 or 18'; and each bracket 40 or 40' comprises a laterally projecting portion 42 or 42' formed with an aperture 43 or 43'. As is clearly shown in Fig. 1, the laterally projecting portions 42 and 42' project toward each other, when the rack is in set-up condition.
- It will be clear that the portions 42 or 42' of the brackets 40 or 40' form supports for the free edges of the respective trays 23, 24 and 25. Preferably, the brackets 40 or 40' are so positioned that, when the organization is assembled, the trays are inclined to the horizontal, as illustrated in Fig. 2.
- 20 The projection of the pins 44 and 44' through the apertures formed in the bracket portions 42 and 42' positively locks the side wing frames 16 and 16' against movement about their hinge axes; thereby making the entire assembled rack 25 extremely rigid.
- When it is desired to fold the rack to transport it, the pins 44 and 44' are disengaged from the bracket apertures 43 and 43', and the trays

are swung into vertical positions. The side wing frames 16 and 16' are then swung inwardly to lie parallel to, and substantially flat against, the back frame 10; whereby a flat, compact package for transportation is provided.

We claim as our invention:

A display rack comprising a back frame formed of a one-piece tubular member bent into substantially rectangular formation, two side frames each formed of a single tubular member bent to provide a substantially rectangular structure, said side frames being hinged respectively to the uprights of the back frame through the medium of at least two straps surrounding the upright of the back frame and an upright of the side frame to provide a flat folding hinge connection between the side frames and the back frame, a plurality of trays hingedly mounted between the uprights of the back frame and supporting means on each of the front uprights of the side frame for each of said trays interlocking with said trays to prevent the lateral displacement of the side frames relative thereto, and downwardly extending feet on said back frame and each of said side frames for supporting the same in a substantially rigid upright position.

CARL T. LUNDSTROM.

EDWARD A. McLAUGHLIN.
